UNITED STATES PATENT OFFICE.

WILLIAM HENRY LEIMAN AND GEORGE WILLIAM LEIMAN, OF NEWARK, NEW JERSEY.

JEWELER'S WORK-BENCH.

1,249,786.

Specification of Letters Patent. Patented Dec. 11, 1917.

Application filed April 17, 1917. Serial No. 162,814.

To all whom it may concern:

Be it known that we, WILLIAM H. LEIMAN and GEORGE W. LEIMAN, citizens of the United States, and residents of Newark, in the county of Essex and State of New Jersey, have invented a new and useful Improvement in Jewelers' Work-Benches, of which the following is a specification.

The object of our invention is to provide an improved work bench for jewelers' use, in which a single bench can be converted into a double bench or in which the parts may be reversed to use either side of the bench.

A still further object is to provide a bench of the above character in which all of the precious metal dust can be saved in a ready and convenient manner.

A practical embodiment of our invention is represented in the accompanying drawings, in which—

Figure 1 represents the bench in top plan, Fig. 2 represents a front view of the same,

Fig. 3 represents an end view, and

Fig. 4 represents an enlarged detail vertical section taken from front to rear through the bench.

The supporting legs 1, 2, of the bench are surmounted by side frames 3, 4. A bench top 5 is mounted upon the side frames 3, 4, which bench top is built up of a plurality of longitudinally disposed bars glued together along their vertical meeting faces and still further secured by through bolts 6. In the present instance, two of these through bolts are shown.

The arm rest is denoted by 7 and the file pin by 8. The top 5 has recesses 9, 10, extending inwardly from its front edge for removably receiving the arm rest and file pin. It also has corresponding recesses 11, 12, extending inwardly from its back edge for removably receiving another arm rest and file pin when the bench is to be used as a double bench, or the same arm rest and file pin, where the bench is to be used as a single reversible bench.

End coamings 13, 14, are provided for the ends of the table and a back coaming 15 is removably secured to the top and end coamings, as, for instance, by a series of screws 16. This back coaming is recessed at 17 to receive the heads of the bolts 6.

The dust pan 18 forms part of a reversible

drawer which is slidably supported on the 55 bars 19 secured to the side frames 3, 4. The dust pan has upwardly curved marginal walls to eliminate corners where the dust might collect. The front and back bars 20, 21, and the uprising ends 22, 23, of the 60 drawer are undercut so as to overlap the edges of the uprising walls of the dust pan.

The dust pan 18 has a perforated portion 24 through which the dust may be swept into a removable cup 25 supported in a hanging bracket 26 depending from the dust pan. 65

The tool tray 27 is removably positioned in the dust pan 18 and is provided with a wire mesh bottom 28 through which the dust from the tools may escape into the bottom 70 of the pan.

Some of the advantages arising from a jeweler's work bench, such as herein shown and described, are as follows: The table is prevented from warping by its built up construction. Where the table has been made of a single plank it has been found extremely difficult to prevent it from warping under various changes of climatic conditions. Another advantage is the ability to reverse the 80 arm rest and file pin when the front of the top coaming becomes unduly worn. This may be accomplished by removing the back coaming 15 and securing it along the front edge of the table. This bench can also be 85 used as a double bench by removing the back coaming 15 and inserting another arm rest and file pin in the recesses 11 and 12.

The construction and arrangement of the tool tray, dust pan, and cup, insures the saving of practically all of the precious metal dust. 90

It is evident that changes may be resorted to in the form, construction and arrangement of the several parts without departing from the spirit and scope of our invention as claimed; hence we do not wish to limit ourselves strictly to the structure herein shown and described, but

What we claim is:

1. In a jeweler's work bench, an arm rest, a file pin and a top having recesses extending inwardly from both its front and back edges for removably receiving said arm rest and file pin. 100

2. In a jeweler's work bench, an arm rest, a file pin, a top having recesses extending inwardly from both its front and back edges 105

for removably receiving said arm rest and file pin, a removable longitudinal coaming, and means for securing it along either the front or back edge of the top.

5 3. In a jeweler's work bench, an arm rest, a file pin, a top having recesses extending inwardly from both of its front and back edges for removably receiving said arm rest

and file pin, and a reversible drawer including a dust pan.

In testimony, that we claim the foregoing as our invention, we have signed our names this 10th day of April, 1917.

WILLIAM HENRY LEIMAN.
GEORGE WILLIAM LEIMAN.
